N. ECKLES

FAN BLADE MECHANISM

Filed Aug. 13, 1920

UNITED STATES PATENT OFFICE.

NOBLE ECKLES, OF SAN DIEGO, CALIFORNIA, ASSIGNOR, BY DIRECT AND MESNE ASSIGNMENTS, TO RHODE-ECKLES ELECTRIC MFG. CO., INC., OF LOS ANGELES, CALIFORNIA, A CORPORATION OF CALIFORNIA.

FAN-BLADE MECHANISM.

Application filed August 13, 1920. Serial No. 403,186.

To all whom it may concern:

Be it known that I, NOBLE ECKLES, a citizen of the United States, residing at San Diego, in the county of San Diego and State of California, have invented certain new and useful Fan-Blade Mechanism, of which the following is a specification.

My invention relates to fan blades for circulating air for cooling purposes and the objects of my invention are: First, to provide a fan blade mechanism so shaped and constructed that a maximum of efficiency is produced; second, to provide a fan blade which is so constructed and shaped that it provides a minimum of resistance and a maximum air thrust; third, to provide a fan blade of this class which reduces to a large extent the usual hum of the fan blades thus providing a silent running fan; fourth, to provide a fan blade mechanism of this class which is so shaped that it is readily constructed of one piece of sheet metal and fifth, to provide a fan blade mechanism of this class which is very simple and economical of construction, durable, easy to operate, easy to install, efficient in its action and which will not readily deteriorate or get out of order.

With these and other objects in view as will appear hereinafter my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a perspective view of a fan motor showing my fan mechanism in operative position thereon; Fig. 2 is an enlarged front elevational view of my fan mechanism positioned ready for installation on the motor shaft; Fig. 3 is an edge elevational view at a right angle thereto; Fig. 4 is a sectional view through 4-4 of Fig. 2; Fig. 5 is a similar view through 5-5 of Fig. 2 and Fig. 6 is a similar view through 6-6 of Fig. 2.

Similar characters of reference refer to similar parts and portions throughout the several views of the drawings.

My fan blade mechanism consists of the blade portions 1 and 2, narrowing contracting portions 3 and 4, short curve portions 5

and 6, intermediate base portion 7 and journal member 8.

The fan blade mechanism is constructed of thin sheet metal in one piece forming two opposed blades extending in opposite directions from the journal portion. The portions 1 and 2 are broad and curved and are set on an angle in opposite directions from each other, similar to an aeroplane propeller and gradually taper inwardly toward the portions 3 and 4. The front edges of the blades 1 and 2, when revolving, are provided with long curves 1^a and 2^a, while their back edges are provided with short curves 1^b and 2^b and the front edges of the blades are set back at points 1^c and 2^c a considerable distance from the front of the blade mechanism as shown best in Fig. 3 of the drawings and the back portions 1^d and 2^d of the blades, when revolving, are set forward slightly in advance of the base 7 so that the pitch of the blades on the opposite sides gradually increases from the outer end toward the center, while the width of the blades gradually decreases, the metal at the center being bent backwardly as shown best in Figs. 3 and 4 of the drawings, the base 7 being of sufficient width so that the journal member 8 may be secured thereto and the metal rests against the sides of the journal member as shown best in Fig. 4 of the drawings. The journal member may be riveted or otherwise secured to the base which is an integral portion of the blades 1 and 2.

Having thus described my invention what I claim as new and desire to secure by Letters Patent is:

1. A fan blade, comprising a hub portion having a front face which lies substantially in a plane of rotation, and a thrust portion having its leading edge offset from said plane to a large extent adjacent the hub portion, and elsewhere, to an extent which gradually diminishes from the hub portion to the tip, and having its following edge approximately in said plane.

2. A fan blade, comprising a hub portion having a front face which lies substantially in a plane of rotation, and a thrust portion continuous from hub to tip, having its leading edge offset from said plane to a large extent adjacent the hub portion, and elsewhere, to an extent which gradually dimin-

ishes from the hub portion to the tip, and having its following edge approximately in said plane.

3. A fan blade mechanism, including opposed blades, each of the said blades being laterally offset at the hub portion at the leading edge of the said blade relatively to the following edge thereof, said blade extending outwardly in the shape of a transversely warped plane, the pitch of said blade decreasing outwardly proportionate to its distance from the hub portion, said offset decreasing outwardly from said hub portion.

15 4. A fan blade mechanism, including a fan blade laterally offset to a large extent at its leading edge relatively to its following edge at the hub portion of said blade, said blade extending outwardly in the shape
20 of a transversely warped plane, the pitch of said blade decreasing outwardly proportionate to its distance from the hub portion, said offset decreasing outwardly from said hub portion.

25 5. A construction of fan blades, comprising a hub portion adapted to receive a driving shaft, and opposed blades carried by said hub portion and shaped to cause the angularity of their working faces at successive cross sections with the planes of rotation of said sections to decrease outwardly from the hub portion, and having their portions adjacent the hub portion offset therefrom into positions to bear against the shaft.

35 6. A fan blade mechanism, including a metallic member in general straight line form, offset at the middle to form a reinforced hub and provided with oppositely disposed outwardly extending blades having
40 thrust portions from hub to tip in the shape of transversely warped planes the angularity of their working faces at successive cross-sections with the planes of rotation of said sections decreasing outwardly from said
45 hub portion.

has portion.

7. A fan blade mechanism, including a blade member provided with a central channel shaped hub portion and oppositely disposed outwardly extending blade thrust portions integrally secured to said hub portion and shaped from hub to tip in the manner of a warped plane generated by substantially straight lines radiating outwardly from said hub portion, each transverse line in the working face of a blade being inclined with the plane of its revolution in inverse proportion to its distance from said hub portion.

8. A fan blade mechanism, including a
blade member provided with a central channel shaped hub portion and oppositely disposed outwardly extending blade thrust portions secured to said hub portion and shaped in the manner of a transversely warped plane generated by substantially straight

lines radiating outwardly from said hub portion, the working faces of said thrust portions decreasing in transverse curvature and angularity to the planes of rotation outwardly from said hub portion.

9. A device of the class described, including a fan blade longitudinally off-set relatively to the axis of its revolution at its hub portion, its entering edge spaced backwardly a considerable distance from the front face of its hub portion and its trailing edge approximately flush with the face of said hub portion, the cross-section of said blade near its hub portion being so shaped that the portion near its entering edge makes a slight angle with the plane of revolution of the blade, then gradually curves toward and to within a short distance of its trailing edge, gradually increasing its tangential angle with the plane of its revolution and then curves abruptly near its trailing edge in the same general direction making a great angle with its plane of revolution, the angle of the blade near the trailing edge thereof decreasing outwardly from the hub portion. 75 80 85 90

10. A device of the class described including a fan blade longitudinally off-set relatively to the axis of its revolution at its hub portion, its entering edge spaced backwardly a considerable distance from the front face of its hub portion and its trailing edge approximately flush with the face of said hub portion, the cross-section of said blade near its hub portion being so shaped that the portion near its entering edge makes a slight angle with the plane of revolution of the blade, then gradually curves toward and to within a short distance of its trailing edge, gradually increasing its tangential angle with the plane of its revolution and then curves abruptly near its trailing edge in the same general direction making a great angle with the plane of revolution, the angle of the blade near the trailing edge thereof decreasing outwardly from the hub portion, said blade being formed as a warped plane generated by straight lines radiating outwardly from the hub portion. 95 100 105 110

11. A device of the class described, including a blade member having a hub portion and blade portions secured thereto and radiating outwardly therefrom, the cross-section of said blade portions near its hub portion being so shaped that the portion near its entering edge makes a slight angle with the plane of revolution of the blade, then gradually curves toward and to within a short distance of its trailing edge, gradually increasing its tangential angle with the plane of its revolution and then curves abruptly near its trailing edge in the same general direction making a great angle with the plane of revolution, the angle of the blade near the trailing edge thereof decreasing outwardly from the hub portion.

12. A fan blade of the class described, including a blade member having a hub portion and blade portions secured thereto and radiating outwardly therefrom, said hub portion being elongated transversely to its axis of rotation and having side portions extending backwardly from its front face, the leading portion thereof merging with said blade portion in gradual curves, said 5 blade portions being formed in general straight line form radiating from the hub portion, and the curvature and angularity thereof to the plane of revolution decreasing outwardly from the hub portion.
13. A fan blade of the class described, including a blade member having a hub portion and blade portions secured thereto and radiating outwardly therefrom, said hub portion being elongated transversely to its 10 axis of rotation and having side portions extending backwardly from its front face, the leading portions thereof extending angularly to the longitudinal axis of the blade portion merging with said blade portion in gradual curves, said blade portions being formed in general straight line form radiating from the hub portion, and the curvature and angularity thereof to the plane of revolution decreasing outwardly from the 15 hub portion.
14. A fan blade of the class described, including a blade member consisting of a hub portion and blade portions secured thereto and radiating outwardly therefrom, said hub portion being elongated transversely to its 20 axis of rotation, the axis of its transverse elongation extending angularly to the longitudinal axes of said blade portions, the entering edges of said blade portion near 25 said hub portion being considerably off-set backwardly from the front face of said hub portion and their trailing edges near said hub portion coming substantially flush with the front face of said hub portion, the angularity of the blades to their plane of revolution decreasing outwardly from the hub portion.
15. A fan blade of the class described, including a blade member consisting of a hub 30 portion and blade portions secured thereto and radiating outwardly therefrom, said hub portion being elongated transversely to its axis of rotation, the axis of its transverse elongation extending angularly to the longitudinal axes of said blade portions, the entering edges of said blade portion near 35 said hub portion being considerably off-set backwardly from the front face of said hub portion and their trailing edges near said hub portion coming substantially flush with the front face of said hub portion, the angularity of the blades to their plane of revolution decreasing outwardly from the hub portion.
16. A fan blade of the class described, including a blade member consisting of a hub portion and thin metallic blade portions secured to opposite sides thereof, said hub portion being substantially channel shaped with the flanges forming said channel extending inwardly, and the axis of said channel portion extending angularly to the longitudinal axes of said blade portions.
17. A fan blade of the class described, including a blade member consisting of a hub portion and blade portions secured to opposite sides thereof, said hub portion being 40 transversely elongated and the axis of said elongation extending angularly to the longitudinal axes of said blade portions.
18. A fan blade of the class described, including a blade member having a hub portion and blade portions secured thereto and radiating outwardly therefrom, said hub portion being elongated transversely to its axis of rotation and having side portions extending backwardly from its front face, the leading portions thereof connecting with said blade portions, said blade portions being 45 formed in general straight line form radiating from the hub portion, and the transverse angularity thereof to the plane of revolution decreasing outwardly from the hub portion.

In testimony whereof, I have hereunto set my hand at San Diego, California, this 3rd day of August, 1920.

NOBLE ECKLES.
